CLAIM

I claim the ornamental design for a battery charger carrying case, as shown and described.

DESCRIPTION

FIG. 1 is a top perspective view of the battery charger carrying case showing my new design.

FIG. 2 is a bottom perspective view thereof.

FIG. 3 is a right side view thereof.

FIG. 4 is a left side view thereof.

FIG. 5 is a front view thereof.

FIG. 6 is a back view thereof.

FIG. 7 is a top view thereof.

FIG. 8 is a bottom view thereof.

FIG. 9 is top perspective view with the strap unbuckled; and, FIG. 10 is a perspective view of the battery charger carrying case with the battery charger strapped in the case and the front pocket opened.

The broken lines on the battery charger carrying case represent stitching. The broken line showing of a battery charger in FIG. 10 is included for the purpose of illustrating environment and forms no part of the claimed design.
